UNITED STATES PATENT OFFICE.

LOUIS ALLEN ABRAMSON, OF NEW YORK, N. Y.

CLOSURE FOR DOORWAYS.

1,415,854.

Specification of Letters Patent. Patented May 16, 1922.

Application filed April 4, 1921. Serial No. 458,472.

To all whom it may concern:

Be it known that I, LOUIS ALLEN ABRAMSON, a citizen of the United States, and a resident of the borough of Bronx, county of Bronx, city and State of New York, have invented certain new and useful Improvements in Closures for Doorways, of which the following is a specification.

While adaptable to other purposes and conditions of use, my improvements relate more particularly to, and are designed primarily for, closures for use in conjunction with doorways to patients' rooms or other apartments in hospitals, sanatoria and similar institutions, where seclusion consistent with facility of ingress and egress, ventilation and sanitation generally are desiderata; and even more especially for use in surgical institutions in which it is frequently desirable to transfer a patient to an operating room without removal from the bed occupied by the subject, and with the least possible disturbance or difficulty.

In order to render feasible such transfer of a bed ridden patient it is customary to provide doorways of a width fully sufficient to admit of the passage of the beds ordinarily provided for occupants, such beds being approximately four feet or so in width, so that a doorway of maximum width, adapted to this purpose, is in excess of that requisite for ordinary purposes of entrance or exit. Hence a door of ordinary construction made to fit an aperture of this character is unwieldy and cumbersome for general use, and impractical in a utilitarian sense.

My improvements are designed to eliminate the difficulties heretofore incidental to the use of closures fitted to such large doorways, and to provide for all contingencies relating to the use thereof, in such manner that my new form and construction of closure may function as an emergency door, as an ordinary door for ingress and egress under normal conditions of use, or as a means of ventilation while screening the apartment from direct observation, all as hereinafter fully set forth,—the invention consisting in the specific construction, arrangement and combination of parts whereby these desirable results are attained in a practicable manner.

In the accompanying drawings,

Fig. 1, is an isometrical perspective showing a doorway closure embodying the essential features of my invention;

Fig. 2, is a detail of a bracket support provided for the medial door when the door sill is dispensed with;

Fig. 3, is a sectional detail of the upper pivotal support for the medial door;

Fig. 4, is a horizontal section taken upon plane of line 4—4, Fig. 5;

Fig. 5, is an elevation of a portion of the doorway closure shown in Fig. 1, with the medial door closed;

Fig. 6, is an isometrical view of the lower portion of my sill-less doorway closure;

Fig. 7, is a front elevation of one of the screen hinge supports;

Fig. 8, is a section taken upon plane of line 8—8, Fig. 7;

Fig. 9, is a section taken upon plane of line 9—9, Fig. 8;

Fig. 10, is a section taken upon plane of line 8—8, Fig. 7, without the hinge bracket;

Fig. 11, is a sectional detail of the weight-sustaining spring-bolt provided on the maximum door.

In several figures of the drawings the letter D, is used to designate a doorway of maximum width for use in an emergency, as for instance, the passing therethrough of a bed when desirable for reasons herein stated; E, represents the emergency door of the full width of said doorway D; M, the medial door for ordinary use, and S, an auxiliary screen door for use when it is desirable to maintain the medial door in open position, and at the same time prevent observation of the interior of the apartment.

The emergency door consists essentially of a frame comprising the vertical members e, e', and a connective top member e². It may also be formed with a bottom or sill member e³, as indicated in Figs. 1, 4 and 5, of the drawings, although the sill e³, may be dispensed with, as in Figs. 2 and 6, in which case a foot bracket e⁴, is substituted in lieu thereof for the lower pivotal support of the medial door M, as shown in said Figs. 2 and 6,—the upper portion of said medial door M, being pivotally supported on the upper connective member e², of the emer-

gency door E, as indicated in Figs. 1 and 3. In other words, the upper rear edge of the medial door M, may be formed with a pintle m , for engagement with a fulcrum 5 mortise e'' , in the under side of the top member e^2 , of said emergency door E, as shown particularly in Fig. 3; while the lower rear edge of the medial door M, may be fulcrumed, either on the sill member e^3 , 10 of the emergency door E, as in Figs. 1 and 5, or on a bracket e^4 , on the side member e , of said emergency door, as in Figs. 2 and 6, and as hereinbefore intimated. In either case the medial door is preferably, although 15 not necessarily, free to swing in either direction on the emergency door E— e^x , in Figs. 1, 2, 5 and 6, representing a vertical spring pivot of the automatic closure type of well known construction and use in the 20 art. In this connection it is to be noted that by the use either of the bracket e^4 , or of a sill e^3 , integral with the emergency door E, as a means of support for the lower portion of my medial door M, I avoid projections 25 above the floor that would be obviously objectionable in case of removal of a bed-ridden patient through the doorway.

The emergency door E, is hinged, as indicated at f , Fig. 4, to one side member f' , of 30 the doorway frame F, a plurality of suitable hinges being used for the purpose; or said emergency door E, may be otherwise fulcrum-mounted and supported on one side of the doorway D, by equivalent mechanical 35 expedients if preferred,—the essential feature in this respect being the provision of means whereby the duplex door E, M, considered in a unitary sense, may be opened up to render the full area of the doorway D, 40 available in case of emergency.

As this duplex structure of door E, M, is necessarily heavy, and as the emergency frame or portion E, thereof is normally closed, I provide the otherwise free member 45 e' , of the door E, with a spring bolt b , of well known general construction and operation, but which also may be utilized as indicated more particularly in Fig. 11, to relieve the hinges f , of undue or unnecessary strain, 50 and thereby prevent sagging etc., the bolt b , being provided with a latch lever b' , whereby it may be retracted against the resistance of the lift or take up spring b'' , (Fig. 11), when it is desired to swing open 55 said emergency door in its entirety. In order to enable the bolt b , to thus perform the double function of a spring bolt, and of a take up or lift to compensate for the aggregate weight of my composite doorway closure, considered as a unitary structure, and to relieve the hinges f , of undue normal strain as stated, I form my bolt b , with an annular collar b^x , which, when the bolt b , 60 is lowered, will bear against a floor mortise

plate p , as shown in said Fig. 11, and I also 65 interpose said lift spring b'' , between said annular collar b^x , and a fixed shoulder b^2 , on the door itself, as also illustrated in said Fig. 11, of the drawings, which spring b'' , 70 must be of sufficient expansive strength and resilience to act as a counter-poise, substantially as and for the purpose set forth.

My so called medial door M, mounted as above stated on the emergency door E, as a supporting frame, is of course designed 75 for normal use as a means of entry to, or departure from, the apartment provided with the maximum or emergency width of doorway D. Should it be desired to close the apartment so, as to afford a patient absolute privacy and freedom from corridor noise or disturbance, my medial door M, is kept shut.

In certain contingencies, however, as where 80 a patient is convalescent, etc., it may be desirable to leave the normal medial door M, open with the emergency door E, locked in closed position, and for this reason I provide my emergency door E, with an auxiliary screen door S, positioned and made preferable of such height as to afford privacy from 85 external observation as of the interior of the apartment from the corridor while admitting light, air, etc., therefrom. As this auxiliary screen door S, is also an emergency 90 expedient, I support it demountably on the emergency door E, preferably by means of stud posts a , positioned in concealed boxes a' , countersunk in the side member e , of the emergency door, as shown more particularly 100 in detail in Figs. 7 to 10, of the drawings, inclusive, which represent a single hinge mount of this character. In this construction of a demountable hinge support the stud post a , is enclosed in and is integral with 105 a box a' , provided with a spring-controlled shutter a^2 , which automatically closes the box in the absence of the detachable bracket arm h , on which the spring hinge h' , is mounted, said spring hinge h' , being of a 110 well known commercial type, and being attached to the frame s , of the screen as indicated particularly in Fig. 7.

From the foregoing it will be seen that, by 115 my specific construction and arrangement of parts, I attain a maximum doorway closure especially adapted to meet all the varying requirements and exigencies incidental to use in a hospital or similar institution, and by means which are simple and conveniently 120 manipulatable.

It is to be understood that by the term "emergency door" as herein used I mean to designate a primary major closure of the full area of the fixed maximum 125 doorway involved; and that by the term "medial door" I mean to designate a normal closure for a supplementary medial doorway

provided within the area of said primary major emergency door, substantially as herein disclosed.

What I claim as my invention and desire 5 to secure by Letters Patent is,

1. A closure for doorways of the character designated, comprising a major emergency door of maximum fixed doorway area, said emergency door being formed with a supplementary normal doorway, and a medial door pivotally mounted on said emergency door and adapted to function as a closure for said supplementary normal doorway, together 10 with an auxiliary screen door demountably supported on said major emergency door, and adapted to partially close said normal doorway, said medial door and screen door hinged to extend entirely across the door opening and to swing in opposite directions, 15 20 for the purpose described.

2. In a closure for doorways of the character designated, the combination of a major emergency door of maximum fixed doorway area formed with a supplementary normal doorway, a medial door pivotally mounted on said major emergency door, and means on said major emergency door for locking the same in closed position and counterpoising the weight thereof, together with an auxiliary screen door demountably supported 25 30 on said major emergency door to swing in the opposite direction thereto and adapted to extend entirely across the door opening and to partially close said normal doorway, 35 for the purpose described.

3. A closure for a sill-less doorway of the character designated, comprising a hinged major emergency door of maximum fixed

doorway area, said emergency door being formed with a sill-less normal supplementary doorway and with a foot bracket, and a medial door pivotally mounted on and between said foot bracket and the upper member of said emergency door and adapted to act as a closure for said sill-less supplementary normal doorway, together with a spring bolt on said emergency door adapted to lock the same in closed position and to counterpoise the weight thereof and of the parts mounted thereon, and a screen door of less 40 45 50 height than the medial door and mounted on said major emergency door and adapted to swing independently of said medial door, for the purpose described.

4. A closure for a sill-less doorway of the character designated, comprising a major emergency door of maximum fixed doorway area, said emergency door being formed with a sill-less supplementary normal doorway and with a foot bracket, a medial door pivotally mounted on and between said foot bracket and the upper member of said emergency door and adapted to act as a closure for said sill-less supplementary normal doorway, an auxiliary screen door demountably 55 60 65 supported on said major emergency door, and hinged to swing in the opposite direction independently thereof, and a spring bolt on said major emergency door adapted to lock the same in position and to counterpoise the weight thereof and of the parts mounted thereon, for the purpose described. 70
